UNITED STATES PATENT OFFICE.

ENOCH P. STEVENS, OF CHICAGO, ILLINOIS, ASSIGNOR TO AMERICAN ARCH COMPANY,
OF NEW YORK, N. Y., A CORPORATION OF DELAWARE.

MARGINAL BRICK.

1,229,389.

Specification of Letters Patent. Patented June 12, 1917.

Application filed February 11, 1916. Serial No. 77,646.

To all whom it may concern:

Be it known that I, ENOCH P. STEVENS, a citizen of the United States, residing at Chicago, in the county of Cook and State of Illinois, have invented certain new and useful Improvements in Marginal Bricks, of which the following is a specification.

My invention relates to front arch constructions for locomotive fireboxes and has special reference to improvements in the marginal bricks of such arches.

A primary object of my invention is to improve the construction of marginal arch bricks in a manner to adapt a marginal single brick for use in many different positions. In other words, to broaden the working range of such bricks.

A marginal brick occupies the space between the outermost water circulating arch tube and the adjacent side sheet of the firebox. Even in a single firebox the distance between the arch tube and the side sheet varies from end to end of the box. It has been the practice to install marginal bricks upon the tubes and against the side sheets and to compensate for the varying distance between the side sheet and arch tube by the use of bricks of different lengths at the different points. And likewise, it has been necessary to employ marginal bricks of different lengths in different fireboxes.

It is desirable to limit the number of sizes or patterns of bricks which are required to construct arches in the differing fireboxes of the locomotives, and I perceive that the difficulty encountered in ordinary practice may be obviated by modifying the primary form of such marginal bricks in such manner as to adapt them to act properly in many different positions and at various inclinations upon the arch tubes and side sheets.

With this end in view, I have devised, and my invention consists in, a marginal brick for locomotive firebox arches, having an end formed to rest upon an arch tube and having an under or outer side for engagement with the side sheet of a firebox, and which substantially conforms to the arc of a circle which extends from end to end of the brick. While the special shape here defined is the most desirable form for the brick, the following description will show that the invention is not specifically limited to a brick which is curved in conformity with a true arc of a circle.

My invention will be readily understood on reference to the drawings which form part of this specification; and in which, Figure 1 is a vertical transverse section of a portion of a locomotive firebox, disclosing two water-circulating arch tubes and a firebox side sheet in combination with a main arch brick and a marginal brick, embodying my invention;—Fig. 2 is a plan view of the marginal brick inverted to show the bottom thereof;—and Fig. 3 is a cross section of the marginal brick on the line X—X of Fig. 1.

Further referring to the drawings, 2 represents one of the side sheets of a locomotive firebox;—3 is the outermost arch tube;—and 4 is an intermediate arch tube. It will be understood that these arch tubes are in substantial parallelism with the side sheet, *i. e.*, longitudinally of the firebox. It will also be understood that the arch tubes are inclined forwardly and downwardly in the firebox.

The main or arch body brick, A, may be of any suitable design, but preferably has socketed ends, a^1 , engaged with respective tubes, 3, and 4. So far as the present invention is concerned, it is only necessary that the body brick, A, shall be of a formation and weight sufficient to cause it to maintain its position on the arch tubes, 3 and 4. This is necessary because, as hereinafter explained, the end portion, a^2 , of the brick serves as an abutment for the marginal brick, B. As before stated, the distance between the tube, 3, and the side sheet, 2, often varies in different parts of the same firebox, due to the fact that the arch tube, 3, is in substantial but not strict parallelism with the side sheet. It is also well known that there is at present no standard or determined spacing for the arch tube and side sheet, and hence different spacings are encountered in practically every locomotive in which arch bricks are installed. I have indicated a variation in spacing by the vertically dotted line, 2', which represents another side sheet in a different location with respect to the outer tube, 3.

The brick, B, is of a width substantially the same as that of the brick, A. At its inner end it has a bearing corner or rib, b^1 . Starting from this point, the bottom of the brick is curved preferably upon a line, b^2 , which is substantially the same as the curva-

ture of the circumference of the tube, 3. From that point the curve of the bottom conforms to an arc of a circle, b^3 , which continues uninterruptedly to the end, b^4 , of the 5 brick. Obviously, the bottom, which is so curved, is adapted to co-act with the side sheet in any tangential position in which the brick may engage the side sheet. The full lines, and the dotted lines, C, show how 10 the brick, B, acts in widely different positions.

For sake of economy and strength, I prefer that the top or inner side, b^5 , of the brick shall conform to the arc of a circle 15 which extends from the end, b^4 , to the inner end, b^6 . The shape of the end, b^6 , is in practice determined by the shape of the abutting portion, a^2 , of the body brick with which the brick, B, is to be used. As a rule, 20 the end, b^6 , is disposed at an obtuse angle to the top surface, b^5 . That form allows the brick to be elevated to the position shown by dotted lines, or further, without interference with the upper corner of the body brick, A.

25 In the preferred construction of the brick, B, the middle thereof is of the greatest thickness and the thickness diminishes toward the free end, b^4 .

I reduce the bearing of the brick upon the 30 side sheet virtually to a single point by thinning the brick from its middle line toward its edges, leaving only a broad middle rib, b^7 , to bear against the side sheet, as best shown in Fig. 3. The strength of the brick 35 is retained by merging the rib with the body of the brick adjacent the inner end thereof.

This crescent-like marginal brick pivots 40 freely upon the top of the arch tube, 3, and against the end of the brick, A. It is not only capable of use in various positions, as explained, but also adapts itself to the changes which take place between the side sheet and the tube, 3, during the working of the locomotive.

45 It will doubtless occur to the reader that the top of the marginal brick might better conform to the straight dotted line, D, and indeed the brick may be so formed, but in that case it will be found that the weight 50 of the brick represented in full lines is much

to be preferred, and furthermore I find that the crescent-formed brick is stronger by reason of the fact that a brick of that form is more uniformly burned in the kiln and is not subjected to the effects of uneven 55 shrinkage.

Having thus described my invention, I claim as new and desire to secure by Letters Patent:—

1. A marginal brick for locomotive fire- 60 box arches having its bottom substantially conformed to a single arc of a circle extending from end to end thereof, save that the inner end of said brick is provided with a downturned bearing-rib for co-action with 65 an arch tube and the end of an arch body brick thereon.

2. A marginal arch brick of crescent-like 70 form in side elevation and having its inner end formed for engagement with the top of an arch tube and the end of an arch body brick.

3. A marginal arch brick of crescent-like 75 form in side elevation and having a bearing rib at its inner end adapted for engagement with the top of an arch tube and the end of an arch body brick thereon.

4. A marginal arch brick of crescent-like 80 form having a middle bearing rib on its bottom and at its inner end provided with a bearing rib at right angles to said middle rib whereby the inner end of said brick is adapted for support by an arch tube and 85 for engagement with an arch body brick resting thereon.

5. A marginal arch brick of crescent like 90 form having a middle bearing rib on its bottom and at its inner end provided with a bearing rib at right angles to said middle rib adapting said end for engagement with the top of an arch tube and an arch body brick thereon, and the inner end of said brick being formed at an obtuse angle to the top of the brick whereby the inner end of 95 said brick is adapted for support by an arch tube and engagement with an arch body brick resting thereon.

In testimony whereof, I have hereunto set my hand this 25th day of January, 1916.

ENOCH P. STEVENS.
